US00D712433S

(12) **United States Design Patent**
Okumura et al.

(10) **Patent No.:** **US D712,433 S**
(45) **Date of Patent:** **** Sep. 2, 2014**

(54) **DISPLAY PANEL OR SCREEN WITH
GRAPHICAL USER INTERFACE**

(71) Applicant: **Sony Corporation**, Tokyo (JP)

(72) Inventors: **Mitsuo Okumura**, Tokyo (JP);
Tomohiro Ishii, Tokyo (JP); **Makoto
Niijima**, Tokyo (JP); **Taku Sugawara**,
Tokyo (JP); **Kenichi Yoneda**, Tokyo (JP)

(73) Assignee: **Sony Corporation**, Tokyo (JP)

(**) Term: **14 Years**

(21) Appl. No.: **29/442,722**

(22) Filed: **Apr. 26, 2013**

(57) **CLAIM**

The ornamental design for a display panel or screen with a graphical user interface, as shown and described.

DESCRIPTION

FIG. 1 is a front elevational view of a first embodiment of a display panel or screen with a graphical user interface showing our new design; and,

FIG. 2 is a front elevational view of a second embodiment thereof.

The dot-dash broken line in all views showing of a display panel or screen is for illustrative purposes only and forms no part of the claimed design.

1 Claim, 2 Drawing Sheets
